(57) **CLAIM**

The ornamental design for a combined bracket and saddle hose hanger, as shown and described.

DESCRIPTION

FIG. 1 is a perspective view of the combined bracket and saddle hose hanger;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the combined bracket and saddle hose hanger shown in use.

The broken lines shown in the drawings illustrate portions of the combined bracket and saddle hose hanger that form no part of the claimed design.

The combined bracket and saddle hose hanger is shown with a symbolic break in its length. The appearance of any portion of the article between the break lines forms no part of the claimed design.

The broken lines in FIG. 8 showing the combined bracket and saddle hose hanger in use illustrates environment and forms no part of the claim.
